BRANDING TOOL

Francis M. James, Leon, Kans., assignor of twenty-four per cent to Walter A. Wylie and twenty-four per cent to Minnie Niles, both of Wichita, Kans.

Application August 8, 1938, Serial No. 223,667

2 Claims. (Cl. 158—14)

My invention relates to improvements in a branding tool, and has for its principal object a heating means carried by the branding tool structure for the introduction of heat to the branding iron.

A further object of my invention is to provide a branding tool that will function as a torch when the branding iron is removed.

A still further object of my invention is to provide a branding tool having branding irons that are interchangeable, and means to restrict the burning fuel to the lines of the branding iron, contacting the same as heating means therefor.

A still further object of my invention is to provide a tool as herein set forth, said tool adaptable to branding live stock and other commodity such as logs afloat within a boom or otherwise, as distinguishing means from other logs should the boom break.

These and other objects will hereinafter be more fully explained, reference being had to the accompanying drawings forming a part of this specification, in which like characters will apply to like parts in the different views.

Referring to the drawings:

Fig. 1 is a side view of the branding tool.

Fig. 2 is a plan or top view of Fig. 1.

Fig. 3 is an end view of the tool looking toward the branding iron positioned thereon, parts removed for convenience of illustration.

Fig. 4 is a similar view to that of Fig. 3, the branding iron and supporting disc removed to show the apertures in the chamber head.

Fig. 5 is a side view of the branding iron and disc.

Fig. 6 is an enlarged sectional view taken on line 6—6 in Fig. 4.

Fig. 7 is a rear view of the branding iron disc.

Fig. 8 is an enlarged sectional view taken on line 8—8 in Fig. 3.

Fig. 9 is a sectional view showing a modified form for the branding iron.

Fig. 10 is a similar view to that of Fig. 9 showing another modification of the branding iron.

Fig. 11 is an enlarged cross section taken on line 11—11 in Fig. 8 looking in the direction of the arrows, the fuel chamber fragmentarily shown.

Fig. 12 is an enlarged sectional view of a preferred method of connecting the head to the peripheral chamber wall.

My invention herein disclosed consists of a branding tool comprising a fuel chamber 1 to which is connected a shank concentrically and axially extending therefrom as shown in Figs. 1

and 2, the shank comprised of a pair of members 2, spaced apart and arcuate in cross section to conform to a body of a tank 3 seated therebetween, and being clamped therein securely by a bolt 4 rearward of the end of the tank extending through each of said shank members, by which means the said tank is easily removed and replaced. Between the outer end of said shank members is secured an end portion of a handle 5 through the medium of a bolt 6. The outer end of said handle 10 has a grip element 7 secured thereto as a convenient means to determine the vertical position of the branding iron.

The said tank 3 is preferably cylindrical in form to align with the shank members and to be partially concealed thereby as a nonobstructive feature during manipulation of the tool, the tank adapted to contain volatile liquid to be placed therein by removing cap 8, which is fluid tight sealing means for its respective opening, and the said tank at the rear end thereof has an air pump with a plunger 9 by which means the fuel is placed under pressure, compressing the liquid to cause prompt ejection thereof through a pipe 10 connecting said tank to the fuel chamber 25 later described, it being understood that the tank is partially filled with the volatile liquid to provide an air space for the compression above referred to.

The said pipe 10 has a valve 11 functioning as a cut-off, and, to govern the flow of liquid through said pipe, the said pipe axially extends from the tank, entering the chamber wall A concentric thereto, as shown in Figs. 2 and 8, at which point there is a sleeve 12 secured to said wall, extending 35 inward therefrom, and in which said pipe extends, the sleeve being greater in diameter to permit a plurality of apertures 13 in the wall of the chamber communicating with the sleeve, and the said sleeve to function as an air intake, and being controlled by a rockable cut-off plate 14 that turns on pipe 10, the said plate being apertured to register with the first said apertures, whereby the flow may be partially or entirely cut off by turning the plate.

Positioned in the fuel chamber is a vapor pipe 15, one end of which extends outward of the chamber and beneath said pipe 10, as at 16, said end being slotted to function as a burner, generating the liquid into a vapor as it enters the fuel 50 chamber, said pipe 15 being fed by vapor from the chamber.

The fuel chamber, consisting of a rear wall A and a head B, spaced apart and being connected by a peripheral wall C that is arcuate in form 55

with respect to cross section, will function as a torch or burner, but to such form I do not wish to be restricted. The said arcuate portion adjacent the head preferably has a shoulder D, as shown in Fig. 12, as a convenient means to assemble the fuel chamber and parts extending therein. The head B is finely and closely apertured throughout its area as at E to form jets through which the gaseous fuel flows and may be partially sealed by a disc 17 seated thereon and retained in registry with the head by a flange 18, extending therearound, terminating on a plane with the outer side of said disc, and the said disc is supporting means for a branding iron 19 secured thereto by appropriate legs 20, spacing the iron a short distance from the disc, and the said disc to be slotted as at 21, conforming to the lines of the iron and directly thereunder; the said slot passing through the disc is means to open the jets in registry therewith, so that the flames of the burning fuel will pass through the slot in direct contact with the inner portion of the branding iron as heating means therefor.

It will be seen that the said branding irons may vary in cross section as shown in Figs. 8, 25 9, and 10. Fig. 8 shows the preferred way which is channeled or U-shaped in cross section, and being so arranged, the flames will enter the channel, heating the same quickly to a desired temperature, while in Fig. 9, the inner edge of the iron is broad and against which the flames will impinge, transmitting heat therethrough. Fig. 10 shows the iron as tapering toward the slot, by which form the flames may divide, extending 30 along each side a short distance, which would result in quickly heating the outer extremity thereof.

It will be understood that the said branding iron disc is readily removed, replaced and secured by a pair of pins 22, radially extending 40 and diametrically positioned on the disc to engage in their respective bayonet slots 23, diametrically positioned in the annular flange.

Branding irons are specially formed as identifying means for ownership of property; therefore, the slot passing through the disc must conform to and be in registry with the inner por-

tion of the branding iron, and the head, being apertured as above described, is means to insure ample flow of the gaseous fuel through the slot to heat the iron, while all other apertures are closed.

While I have shown and described a tool having the facilities of a gaseous heating principle, I do not wish to be restricted to such alone, as electric current with proper conduction may be arranged, and such other modifications may be employed as lie within the scope of the appended claims.

Having fully described my invention what I claim as new and desire to secure by Letters Patent is:

1. In a branding tool, in combination with a vaporizing burner having a fuel chamber and means to inject vaporized fuel into the chamber and an apertured head to close the chamber, the apertures being fine with respect to diameter 20 and in close proximity over the surface of the head, a slotted disc and means to secure the disc to snug engagement upon the outer face of the apertured head by which means the flow of burning gas is restricted to the contour of the 25 slot, and an element having a similar contour and means to carry the same in registry with the slot and being spaced outward therefrom to be heated thereby.

2. In a branding tool, in combination with a vaporizing burner having a fuel chamber and means to inject vaporized fuel into the chamber and a removable apertured head to close the chamber and means to secure the head to the chamber, the apertures being fine with respect to 30 diameter and in close proximity over the surface of the head, a plurality slotted disc and means to secure the disc to snug engagement upon the outer face of the apertured head by which means the flow of burning gas is restricted to the 35 contour of each slot, and a branding iron carried by the disc, having a similar contour to that of said slot and carried in registry with said slot and being spaced outward therefrom a short distance and against which the flames will engage as heating means therefor.

FRANCIS M. JAMES.
